UNITED STATES PATENT OFFICE.

HENRY A. JACKSON, OF BROOKLYN, NEW YORK.

FOLDING BABY-CARRIAGE.

SPECIFICATION forming part of Letters Patent No. 291,851, dated January 1, 1884.
Application filed August 30, 1883. (No model.)

To all whom it may concern:

Be it known that I, HENRY A. JACKSON, of Brooklyn, in the county of Kings and State of New York, have invented a new and Improved Folding Baby-Carriage and Canopy Attachment, of which the following is a full, clear, and exact description.

The object of my invention is to provide a new and improved baby-carriage which can be folded very compactly when not in use.

A further object of my invention is to provide a new and improved device for holding a sunshade on a baby-carriage in any desired position.

15 My invention relates to improvements in folding baby-carriages; and it consists in the peculiar construction and arrangement of the parts, as hereinafter more fully set forth, and pointed out in the claims.

20 Reference is to be had to the accompanying drawings, forming part of this specification, in which similar letters of reference indicate corresponding parts in all the figures.

Figure 1 is a longitudinal elevation of my 25 improved baby-carriage, showing it folded. Fig. 2 is a like elevation, partly in section, showing it extended for use. Fig. 3 is a rear view of the same. Fig. 4 is an enlarged cross-sectional view of the axle, and showing the 30 clutch on the handle. Fig. 5 is a perspective view of the hinge-bar and the spring thereon. Fig. 6 is a front elevation, partly in section, of the canopy-bow. Fig. 7 is an enlarged perspective view of the locking and adjusting 35 device for the same.

The carriage body or box is composed of two sections, A A', hinged to each other at the bottom by a hinge-rod, B. A metal band or bar, C, is secured to the back and sides of the section A', and to the free ends of the said band or bar C a bail or U-shaped bar, D, is pivoted, which is adapted to be swung over the section A, the outer end of the said section A being recessed to receive the cross-piece of the said bar D. The said bar or bail holds the upper parts of the two sections A A' together. The springs E are hinged on the ends of the joint-rod B, and the ends of the springs are secured on the axles F and F'. 45 Spiral springs G are coiled around the rod B, and each spring has one end secured to the front section, A, and the other end to the

other section, A', of the carriage-body, the springs having the tendency to swing the bottoms of the sections together. Crossed chains 55 H are secured to the axles F F' and to the outer ends of the bottoms of the sections A A', the said chains preventing undue jolting of the body and holding the same nearly level.

Two reaches, J, are secured to the front 60 axle, F, and are of such length that they can extend to the rear axle, F', the said bars being attached so near the ends of the axles that they can be swung upward past the sides of the body-sections A A'. The free end of each 65 side bar is recessed to fit against the rear axle, F', and to the free end of each side bar a handle, K, is pivoted, which handles have their free ends united by a suitable cross-piece; or the two handles can be made of one piece. 70 Each handle is provided at its pivoted end with a downwardly-projecting curved prong, M, adapted to fit closely on the axle F. The handles K can be swung down in the direction or toward the front of the carriage, as in Fig. 1. 75

A bow, N, is provided in its curved top with teeth R², and with a vertical curved longitudinal slot, N², through which the ferrule O of a sunshade, parasol, or canopy, P, passes, which ferrule is provided at its upper end 80 with a head or button, Q', to prevent it from slipping through the slot. The lower end of the handle Q of the parasol or canopy P is connected with a rod, R, the other end of which is provided with an eye, R', through 85 which one of the uprights of the bow passes. One end of the bow is pivoted to the side of the body-section A', or to the bar or band C. The other end of the bow is provided with a fork, N', which straddles a toothed semicircular 90 frame, S, secured on the top edge of the body-section A', or on the bar or band C. The fork is pivoted by a pintle, d, passing through the center of the semicircular frame S. The prongs of the fork N' are provided with longitudinal 95 slots g, through which a pintle, T, provided with a head at each end, passes loosely. The springs E are at the sides of the body or box, to permit the body being folded.

The carriage is adjusted as follows: When 100 the carriage is in use, the band D is swung over the section A and holds the sections A A' together. The free ends of the side bars, J, rest against the rear axle, F', which is clamped

between the free ends of the bars J and the prongs M of the handles K. The reaches thus hold the axles the required distance apart. If the carriage is to be folded, the handles are swung toward the front of the carriage and the free ends of the reaches J are raised, upon which the springs G and the weight of the sections A A' will swing the bottoms of the said body-sections A A' toward each other until they are in the position shown in Fig. 1, the reaches being inclined upward and backward, and the handles K being inclined toward the front and downward from the upper ends of the reaches J.

The bow N can be inclined toward the front or rear, and can be locked in position by means of the loose pintle T, which passes into one of the teeth of the semicircular frame S.

The canopy or parasol can be adjusted laterally by moving the ferrule of the same toward one end or the other of the slot N², the canopy being held in the desired position by the rod R, the ring R' of which catches on one of the teeth R², formed on the bow.

Having thus described my invention, I claim as new and desire to secure by Letters Patent—

1. A folding baby-carriage constructed with a box formed of two sections hinged to each other at the bottom, and with springs secured to the bottoms of the sections, for swinging the bottoms of the said sections toward each other, substantially as herein shown and described.

2. A folding baby-carriage constructed with a box formed of two sections hinged to each other at the bottom, with hinged supporting-springs jointed at the joint of the box, and with reaches secured to the front axles, and adapted to fit against the rear axle, substantially as herein shown and described.

3. A folding baby-carriage constructed with a box formed of two sections hinged to each other at the bottom, with hinged supporting-springs jointed at the joint of the box, with reaches secured to the front axle and fitting

against the rear axle, and with handles hinged to the free ends of the side bars, substantially as herein shown and described.

4. In a folding baby-carriage, the combination, with the hinged body A A', of the hinged supporting-springs E, the reaches J, secured to the front axle, F, and fitting against the rear axle, F', and the handles K, hinged to the free ends of the bars J and provided with curved prongs M, substantially as herein shown and described. 55

5. In a folding baby-carriage, the combination, with the axles F F', of the hinged body or box A A', the springs E, jointed at the joint of the box, and the U-shaped frame D or bail hinged to the rear section, A', substantially as 60 herein shown and described.

6. The combination, with a baby-carriage, of a bow having a longitudinal slot in its curved top, and of a canopy or parasol having its ferrule passed through the said slot, substantially 65 as herein shown and described.

7. The combination, with a baby-carriage, of the slotted bow N, the canopy or parasol P, the rod Q, and the rod R, provided with an eye, R', mounted on one of the standards of 70 the bow, substantially as herein shown and described.

8. The combination, with a baby-carriage, of the slotted and toothed bow N, the canopy or parasol P, the rod Q, and the rod R, provided with an eye, R', substantially as herein shown and described. 75

9. The combination, in a baby-carriage, of the pivoted bow N, having the end of one shank forked and provided with a slot, g, with 80 the notched or toothed semicircular frame S and the pintle T, substantially as herein shown and described.

HENRY A. JACKSON.
